ADJUSTABLE LATCH OR CLOSURE DEVICE

George L. Eber, New York, N. Y.

Application July 14, 1932. Serial No. 622,376

7 Claims. (Cl. 292—57)

This invention relates to devices for use in connection with relatively movable body parts to adjustably retain said parts together, and particularly, the telescoping members or parts of suitcases, trunks, boxes and the like; and the object of the invention is to provide a latch or closure device consisting of a tubular casing part and a rod slidably mounted in the casing and extending through one end thereof with means 10 for retaining the rod against movement in one direction with respect to the casing, and further to the provision of means for releasing said retaining means to permit sliding movement of the rod in both directions; a further object 15 being to provide a plurality of latching units of the class defined attached to the front and rear sides of telescoping body parts wherein the latching units at the front side of the body part include hasps for engagement with locks for retaining the body parts against separation, and further wherein the units at the back of said body parts include means for forming a hinged or pivotal connection between said body parts; a further object being to provide a latching device of the class described which is of very 20 simple form and construction as well as being simple and positive in operation, permitting the installation of devices of this class in connection with telescoping body parts at the lowest possible cost, and yet producing a strong and durable construction; and with these and other objects in view, the invention consists in a device 25 of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a transverse, sectional view through telescoping body parts, showing two of the latching devices which I employ, with parts of the construction broken away.

Fig. 2 is a front view of a part of the structure shown in Fig. 1 with parts in different positions.

Fig. 3 is a section on the line 3—3 of Fig. 1.

Fig. 4 is a detail view showing one of the rear latching devices in extended position and showing the covered body part in open position.

Fig. 5 is a section on the line 5—5 of Fig. 1; and,

Fig. 6 is a sectional detail view of a modified form of latching device which I employ.

In the drawing I have shown for the purpose of illustrating one use of my invention, telescoping body parts 10 and 11. The part 10 constitutes the main container of a suitcase, trunk, box or the like, and the part 11 the cover which is movable toward and from the container to compact the articles mounted in the body parts as in other devices of this class.

In suitcases and similar telescoping bodies four latching devices made according to my invention are employed, two at the front part adjacent the end portions thereof and two at the back also adjacent the end portions and preferably in transverse alignment with the front latching devices.

The front latching devices consist of a tubular casing 12 having laterally extending flanges 13 facilitating the attachment of the casing to the body part 10 as indicated in Fig. 2 of the drawing. Slidably mounted in the casing 12 is a rod 14 having longitudinally of one side thereof spaced teeth 15 forming a rack, and a spring finger 16 is mounted in the upper end of the casing 12 and retained in position between the back plate 17 and the top cap 18 of the casing, said finger engaging the teeth 15 to hold the rod 14 against upward movement when said rod is in the position shown in Fig. 1 of the drawing. The inner end of the rod 14 is reduced and provided with a slot 19. Mounted on said end of the rod is a key disk 20 having a flat side 21 which rests upon the flat back wall 17 of the casing to prevent said disk from rotating. A spring 22 is mounted on the reduced end of the rod and has one end entering the slot 19 and the other end coupled with the disk 20 after being placed under tension so as to impart rotary movement to the rod when said rod is released as later described.

The rotary movement of the rod 14 is controlled by a transverse pin 23 which cooperates with a pin 24 on the disk 20 as clearly seen in Fig. 5 of the drawing. Pivoted to the upper end of the rod 14 as seen at 25 is a hasp 26, the pivot including a spring 27 which serves to force the hasp outwardly with respect to the body 10 when the hasp is released from a lock device 28 of conventional form. The yoke-shaped projection 26a of the hasp enters the lock casing through an opening 29 formed therein to be engaged by a bolt 30 controlled by a key mechanism and also by a sliding block 31. By moving the block 31 to the right as seen in Fig. 2 of the drawing, the bolt 30 is released from the hasp, allowing said hasp to spring outwardly. When the hasp is released, the spring 110

22 will operate to rotate the rod 14 to move the teeth 15 of the rack out of engagement with the spring 16 and thus permit the free upward movement of said rod and the opening of the cover part 11 which may be moved into a fully opened position by releasing the latch device or devices at the back of the body part 10.

5 The latch devices at the back of the body part 10 differ from those at the front in eliminating 10 the hasp 26 and its associate parts as well as in eliminating the block 20 and spring 22. The casings 12a of these devices are the same as the casings 12 and include the spring fingers 16a which operate in connection with the teeth 15a of the 15 rod 14a.

The rod 14a includes a knurled portion 32 adjacent the upper end thereof by means of which 20 said rod may be rotated to move the teeth 15a out of engagement with the spring finger 16a permitting the upward movement of said rod with respect to the casing as will be understood. A ball 25 end 33 is provided at the upper end of the rod 14a which fits in a hollow block 34 secured to the top cover part 11 to provide a pivotal or hinged connection of the cover part with respect to the rod or rods 14a, said block having slots 35 formed in two walls thereof to receive the shank portion 36 of the rod 14a adjacent the ball 33, permitting the movement of the cover part 11 into the position shown in Fig. 4 of the drawing, it being understood at this time that the block 34 may be 30 so slotted as to vary the opening movement of the part 11 if desired.

It will be understood that in packing the body 35 parts 10 and 11 after the articles have been placed therein, the part 11 will be moved into a position above the part 10 and the rod 14a rotated to bring the same into the position shown in Fig. 1 of the drawing, and the hasp 26 of the rod 14 will be 40 coupled with the lock casing, in which operation, the hasp is rotated to place the spring 22 under tension as said hasp is moved from the position shown in Fig. 2 to that illustrated in Fig. 1.

With the parts thus assembled, the top body 45 part is forced downwardly, causing the rods 14-14a to descend in the casings 12, 12a, the spring fingers 16, 16a passing over the teeth 15, 15a of the rods until such time as the articles 50 are fully compacted within the body parts, after which the downward pressure is released and the rods 14, 14a are automatically locked in position. In opening the body parts, the hereinbefore described operation of releasing the rod 14 and the rod 14a is repeated.

55 In Fig. 6 of the drawing, I have shown a modified form of construction which would be applicable to either or both forms of latch devices shown at the front and rear of the case as in Fig. 1. In this construction, I eliminate the 60 necessity of employing the teeth 15, 15a and the spring fingers 16, 16a, and substituted therefor I employ a cam lock plate 37 pivotally supported in connection with an extension on the back plate 17b of a casing 12b above the top plate 18b of said casing and adapted to cam lock with a rod 14b movable vertically in the casing to support said rod against upward movement, at the same time permitting downward movement of the rod 65 at any time. The cam plate 37 is supported in its operative position by a spring 38 arranged between the lower face thereof and the top plate 18b of the casing. In order to permit upward movement of the rod 14b, all that is necessary is to depress the plate 37 against the tension of the 70 spring 38 to release said plate from the rod.

In the construction shown, I employ a spring 39 within the casing 12b which operates upon a washer 40 secured to the rod to force said rod upwardly when the plate 37 is depressed, it being understood that the downward movement of the rod 14b will operate to compress the spring 39. With this form of construction it will be apparent that the hasp will be attached to the upper end of the rod on the front latch, whereas the rear latch will have the ball end or similar means for providing a pivotal or hinged mounting of the top part 11 in connection with the rod.

80 It will be understood that various other changes in and modifications of the construction herein shown and described may be made within the scope of the appended claims without departing from the spirit of my invention or sacrificing its advantages.

85 Having fully described my invention, what I 90 claim as new and desire to secure by Letters Patent, is:—

1. A device of the class described comprising a tubular casing, a rod slidably engaging said casing and protruding from one end thereof, means at said end of the casing engaging the rod for retaining the same against movement in one direction with respect to the casing, said rod having longitudinally spaced teeth with which said means cooperate, and means for rotating said rod to move said teeth out of engagement with said means, said last named means comprising a spring mounted on the rod within said casing and a disk on the rod and keyed against rotation in said casing.

100 2. A device of the class described comprising a tubular casing, a rod slidably engaging said casing and protruding from one end thereof, means at said end of the casing engaging the rod for retaining the same against movement in one direction with respect to the casing, said rod having longitudinally spaced teeth with which said means cooperate, means for rotating said rod to move said teeth out of engagement with said means, said last named means comprising a spring mounted on the rod within said casing and a disk on the rod and keyed against rotation in said casing, and the outer end of said rod including a hasp pivotally supported in connection therewith.

105 3. A device of the class described comprising a tubular casing, a rod slidably engaging said casing and protruding from one end thereof, means at said end of the casing engaging the rod for retaining the same against movement in one direction with respect to the casing, said rod having longitudinally spaced teeth with which said means cooperate, means for rotating said rod to move said teeth out of engagement with said means, said last named means comprising a spring mounted on the rod within said casing and a disk on the rod and keyed against rotation in said casing, the outer end of said rod including a hasp pivotally supported in connection therewith, and said hasp serving to support the teeth 120 of the rod in operative engagement with said first named means.

110 4. A device of the class described comprising a tubular casing, a rod slidably and rotatably mounted in the casing and projecting from one end thereof, torsional means for rotating said rod in the casing, means on the protruding end of the rod for supporting the same against rotation against the action of said torsional means, and means at the end of the casing through which 115

- the rod projects engaging said rod when held against rotation for limiting the sliding movement of the rod in one direction with respect to said casing and permitting sliding movement of the rod with respect to the casing in the opposite direction.
5. A device of the class described comprising a tubular casing, a rod rotatably and slidably mounted in the casing and projecting through one end thereof, a member at said end of the casing cooperating with tooth-like elements arranged longitudinally of one side of the rod for retaining the rod against movement in one direction with respect to the casing, torsional means for rotating said rod to move said tooth-like projections out of engagement with said member, and means on the protruding end of the rod for supporting the rod with the tooth-like projections in engagement with said member against the action of said torsional means.
10. A device of the class described comprising a casing, a rod slidably and rotatably mounted in the casing with one end of said rod projecting beyond the casing, said rod having longitudinally spaced coupling elements disposed at one side thereof, a spring finger on said casing engaging said coupling elements to retain the rod against longitudinal movement with respect to the cas-
- ing in one direction, and means whereby said rod may be rotated to disengage the coupling elements from said spring finger to permit the movement of said rod in the opposite direction.
15. In containers involving telescoping parts, a coupling device comprising a tubular casing having means for attaching the same to one of the container parts, a rod slidably and rotatably mounted in the tubular casing and projecting from one end thereof, the protruding end of said rod including means for coupling the same with the other container part and for supporting the rod against rotation in said casing, said tubular casing and rod being provided one with longitudinally spaced coupling elements and the other with a spring actuated finger cooperating with said elements in one position of the rod to retain the rod against outward movement with respect to said casing and permitting inward movement of the rod with respect to said casing, and said rod when detached from the container part being capable of rotary movement in said casing to disengage the spring finger from said coupling elements permitting free longitudinal movement of the rod with respect to the casing in both directions.
20. A device of the class described comprising a casing, a rod slidably and rotatably mounted in the casing with one end of said rod projecting beyond the casing, said rod having longitudinally spaced coupling elements disposed at one side thereof, a spring finger on said casing engaging said coupling elements to retain the rod against longitudinal movement with respect to the cas-
